UNITED STATES PATENT OFFICE.

ETHEL P. WESTWOOD, OF NEW YORK, N. Y.

DESIGN FOR A DOLL.

Application filed March 28, 1924. Serial No. 9,092. Term of patent 7 years.

To all whom it may concern:

Be it known that I, ETHEL P. WESTWOOD, a subject of the King of Great Britain, and a resident of the city, county, and State of New York, United States of America, have invented a new, original, and ornamental Design for a Doll, of which the following is a specification, reference being had to the accompanying drawings, forming a part hereof.

In the drawings,—

Fig. 1 is a front view of the doll embodying the design;

Fig. 2 is a rear view thereof; and

Fig. 3 is a side view thereof.

The design comprises the doll body having thereon the wearing apparel substantially as shown. The face may be variously altered without departing from the invention. Both the doll and clothing are made of colored oilcloth, the body being stuffed. The edges and seams are bound with a cloth binding.

I claim:

The ornamental design for a doll, substantially as shown.

ETHEL P. WESTWOOD.
